UNITED STATES PATENT OFFICE.

EARL W. WAGNER, OF BUTTE, MONTANA.

CENTRIFUGAL EXTRACTOR.

Application filed May 20, 1924. Serial No. 714,681.

To all whom it may concern:

Be it known that I, EARL W. WAGNER, a citizen of the United States, residing at Butte, in the county of Silver Bow and State of Montana, have invented certain new and useful Improvements in Centrifugal Extractors, of which the following is a specification.

This invention relates generally to drying machines, and has more particular reference to a machine of the centrifugal type, wherein moisture may be expeditiously discharged from clothes or any form of material in the operation of the machine.

One of the main objects of the present invention is to provide a drier of the above character wherein the material receptacle may be readily removed from the machine for allowing another receptacle to be disposed therein, thereby resulting in a material saving of time, it of course not being necessary to remove the articles from the receptacle, while the same is disposed within the machine, and then again fill the same.

A further and important object is to provide simple and efficient operating means for locking the material receptacle within the machine, and holding the same rigidly therein during the operation thereof.

Yet another object is to provide a particular bearing construction for the rotary material holder, which bearing construction will overcome the great vibration and shaking of the machine, which is a disadvantage now present in practically all forms of centrifugal driers.

A final salient object is to provide a machine of this character that may be manufactured, installed and operated at minimum cost, and one that is not liable to become out of order, the same comprising relatively few parts, and these correlated in such a manner as to reduce the possibility of disarrangement to a minimum.

With the foregoing and other objects in view as the nature of the invention will be better understood, the same comprises the novel form, combination and arrangement of parts hereinafter more fully described, shown in the accompanying drawings and claimed.

In the drawings wherein like reference characters indicate corresponding parts throughout the different views:

Figure 1—is a top plan view of a centrifugal drying machine constructed in ac-

cordance with the present invention, the drive pulley of the machine being removed in order that the before mentioned bearing construction may be more clearly viewed.

Figure 2—is a fragmentary elevational view of the machine, the splash guard belt thereof being shown in an open position, and partly in cross section, whereby when in an open position, the material receptacle may be readily rolled out and upon the floor for allowing a new filled container to be disposed within and associated with the machine.

Figure 3—is a detailed vertical sectional view of the machine taken at right angles to Figure 2, and

Figure 4—is a detailed elevational view of a band locking construction constituting an essential feature of the present invention, whereby the material container may be locked within the machine.

Now, having particular reference to the drawings, 5 indicates the floor of the shop, within which the present machine is to be installed. This floor 5 is formed at an appropriate point with a circular-shaped well or depression 6 of relatively slight depth, said depression or well being itself centrally formed with a circular socket 7.

Disposed within this floor well or depression is the lower end of a skeleton, generally rectangular-shaped metal frame 8 that comprises a lower horizontal flat-like bar 9 that is secured within the well through the medium of heavy bolt connections 10; preferably three vertically extending bars 11 that are integrally joined at their upper ends to a central substantially rectangular shaped plate 12, through the medium of inwardly extending arms or bars 13.

The lower horizontal bar 9 of the skeleton open frame 8 is formed upon its bottom side with a circular head 14 that engages within the socket 11 of the floor well or depression 6 for assisting the bolt securing means in the maintaining of the frame against vibration. Carried by the top side of this head 14 is a suitable ball bearing 15, that is socketed at its top side for the reception of a pintle 16, pendent from the central point of a material basket supporting platform 17, that is preferably of circular shape shown by the dotted lines in Figure 1.

Extending upwardly from diametrically opposite points of this platform edge are arms 18 that are connected at their upper

ends by a cross bar 19. Secured at its lower end to said cross bar is a vertical shaft 20 that extends through a collared opening 21 in the substantially rectangular shaped plate 13 of the open skeleton frame 8, the upper end of this shaft being equipped with a pulley 21, whereby the material basket supporting platform may be rigidly rotated.

Inter-connecting the arms 18 of the platform 17 at one edge thereof are outwardly extending substantially semi-circular shaped spaced bands 22, that prevent the displacement in one direction of the material basket A when the same is supported upon the platform in a manner as clearly indicated in Figures 2 and 3.

Hingedly secured to the forward edge of the arms 18 of said platform 17 are co-operating bands 23 and 24 that are adapted to be secured at their free ends around the basket A by a locking means, in a manner hereinafter more fully described, for preventing the displacement of the basket upon the platform, and its wobbling movement upon the platform during the operation of the machine.

This locking means constitutes the provision of a bail shaped lever 25, that is hinged to the free end of the member 24, and the same is adapted to be engaged through a loop member 26, also hingedly secured to the free end of the complementary member 23. The bail shaped lever 25 is formed at its unhinged end with a handle 27, and it will be obvious that after the basket has been positioned upon the platform, the members 23 and 24 are to be swung inwardly towards each other, after which the lever 25 may be engaged through the loop 26, and the same subsequently swung upon its hinge to the position shown in Figure 1, for maintaining the members 23 and 24 in locked engagement. Upon the inner side of the rigid bands 22 and locking bands 23 and 24 are rubber bumpers 27' that create a wedging action onto the material basket A for an obvious purpose.

In order to prevent the basket from creeping upwardly during the rotation of the platform, the arms 18 of the platform are formed adjacent the upper ends with inwardly extending shoulders 28, Figure 3, that will engage the upper end of the basket.

Adapted to be disposed upon the skeleton frame carrying plate 12 is a shaft bearing 29, through which the drive shaft 20 of the machine is to be extended. This bearing 29 is formed at its periphery with spaced pairs of separated ears 30 and pivotally disposed between the ears of each pair as at 31 is the eyed end of a pin 32.

The four corners of the skeleton frame plate 12 are formed with upstanding ears or lugs 33, each of which is formed with an opening 34, through which loosely engages

the adjacent pin 32. At the eyed ends of these pins, the same are screw threaded for receiving nuts 35, and surrounding these pins between said nuts and said ears or lugs 33 are expandable coiled springs 36, that co-operate with each other in maintaining the bearing 29 centered, and at the same time taking up the vibration incident to the rapid rotation of the material supporting platform.

It will be obvious that the position of the nuts 35 upon these pins will result in the proper tensioning of the springs 36.

Surrounding the machine is a sheet metal substantially cylindrical shaped splash guard 37, that is formed with an outlet opening for the basket, the same adapted to be closed during the operation of the machine, through the medium of a door 38.

The material basket A is of course to be of wire mesh or other foraminous material, and the same is mounted upon suitable wheels to facilitate the removal or positioning of the same with respect to the platform 17.

This platform 17 must be on a level to the floor surface 5, and it will be clearly apparent from the foregoing, that after the moisture has been extracted from the material in one basket, the same may be rolled off of the platform onto the floor surface and another basket rolled thereon, and subsequently locked in the machine, and the same subjected to a centrifugal action.

I do not wish to be limited to the specific structural details shown in the drawings and set forth in the specification, insomuch as in the future practice of the invention, departures may be had therefrom, without effecting the spirit and scope of the appended claims.

Having thus described my invention, what I claim as new, and desire to secure by Letters Patent, is:

1. In a centrifugal drier of the character described, a vertically positioned rigid frame anchored at one end to a base, a second frame disposed within said rigid frame for rapid rotation, said second frame including a material basket supporting platform, means upon one side of said second frame for limiting the movement of the material basket in one direction, means at the other side of said second frame for securing the basket upon the platform, and means whereby said second frame may be rapidly rotated.

2. In a centrifugal drier of the character described, a vertically positioned rigid frame anchored at one end to a base, a second frame disposed within said rigid frame for rapid rotation, said second frame including a material basket supporting platform, means upon one side of said second frame for limiting the movement of the material basket in one direction, means at the other side of said second frame for securing the basket upon the platform, and means whereby said second frame may be rapidly rotated.

terial basket in one direction, means at the other side of said second frame for securing the basket upon the platform, means whereby said second frame may be rapidly rotated, 5 and a splash shield disposed around the rigid frame and provided with a door opening, whereby the material basket may be passed therethrough.

3. In a centrifugal drying machine of the 10 character described a vertically disposed skeleton frame anchored at one end to a base, a second open frame disposed for rigid

rotation within said first mentioned frame and including a material basket supporting platform, a shaft extending vertically from 15 said second frame passing through an opening in the upper portion of said rigid frame, a laterally movable and cushioned bearing for said shaft disposed upon the upper member of said rigid frame and means carried 20 by said frame, whereby the second frame may be rapidly rotated.

In testimony whereof I affix my signature.
EARL W. WAGNER.
